UNITED STATES PATENT OFFICE.

MAYNARD F. MACDONALD, OF VICTORIA, BRITISH COLUMBIA, CANADA, ASSIGNOR TO JUPITER SPARK PLUG COMPANY, OF SEATTLE, WASHINGTON, A CORPORATION OF WASHINGTON.

SPARK PLUG.

Application filed March 31, 1925. Serial No. 19,610.

My invention relates to spark plugs and particularly to plugs of the general type shown in my Patent No. 1,513,057, issued October 28, 1924.

I have found in connection with plugs of this type; employing a ball-ended or otherwise enlarged electrode cooperating directly with the apron depending from the lower end of the shell, that instead of firing about the entire circumference of the ball the spark tends to jump at one or two places, hence it is not important that the ball be employed to induce a multiplicity of sparks; but I have found that the ball is chiefly desirable for the directional effect it has on the gases passing through or past the spark gap and out of the ports in the apron. I have found, too, that the discharge from the circumference of a ball-ended electrode to the rim or end of the apron has a tendency to be weak and ineffectual, hence it is desirable to concentrate the spark. It is the chief object of the present invention, therefore, to retain the advantages of my former plug in that it prevents fouling through the action of a draft of gases past the spark gap and over the end of the insulator, and having the additional advantage of a hot, concentrated spark.

A further object is so to position two complementary electrodes in a plug of this character, that they will best cooperate with each other to produce a hot, "fat" spark.

The means by which these objects are attained are shown in a number of forms in the accompanying drawings, wherein:

Figure 1 is an axial section through one form of plug;

Figure 2 is an underside view of the same form;

Figure 3 is a side elevation with parts broken away of a modified form;

Figures 4 and 5 are, respectively, a side elevation with parts broken away, and an underside view, of another modification; and

Figure 6 is a side elevation, with parts broken away, of another modification.

In general my invention is similar in form and in principle of operation to my previous invention. As shown, a porcelain insulator 1 has extending through it a positive electrode 2, the porcelain projecting from its seat at 31 within an externally threaded

shell 3, and being held therein by a gland 55 30 threading into the upper end of the shell and closely embracing the insulator 1. Such a construction is common in the art and any suitable equivalent thereof may be employed. As in my former invention the shell 3 is provided with a depending apron 32 having ports 33 therethrough positioned above the lower end of the electrode 2 and preferably being outwardly flared, at their upper edges at least, as indicated at 34.

Referring to Figures 1 and 2, it will be seen that the electrode 2 has a ball 22 formed upon its lower end, and preferably positioned at about the lower end of the apron 32, or at least well below the upper 70 edges of the ports 33. The ball is not large enough to cooperate with the apron 32 to form a spark gap therebetween, but the electrode 2 may have a tip 21 extending slightly below the ball, and a negative electrode 35 secured in the apron extends toward and cooperates with the tip 21 to form a spark gap 23 therebetween. Thus the ball serves to part or deflect the gases as they are forced upward, and to direct them upwardly and 80 outwardly uniformly in all directions, and through the ports 33, the flared walls 34 of these ports assisting in thus directing the gases in a smoothly curved path, as is indicated by the arrow A in Figure 1, and in 85 fact, by its outrush through these flared ports, creating a suction in all parts of the chamber 25 within the shell. The ball being of small diameter, the spark gap is thus substantially in the direct line of these 90 gases, and, as in my former invention, they serve to keep the sparking points clear and free of oil or carbon deposits.

A further function of a deflector at the lower end of the electrode 2, typified by the 95 ball 22, is the direct protection of the end of the insulator 1 from carbon which would tend to accumulate thereon, and which would eventually short-circuit the plug by forming a connection between the electrode 2 and the shell 3, and the indirect protection of the insulator from carbon deposits by creating a suction which appears to remove such deposits. The length of time required for such short-circuiting naturally will vary with conditions found in a given engine, but in some engines it has been found necessary 100 to clean plugs daily to avoid this, while

in some airplane motors even a few hours' use of plugs, especially idling while warming up the motor, will foul them. I have found that such a deflector will part the stream of gases, directing them outward through the flared holes 33, away from the insulator, and away from the re-entrant chamber 11 often formed at the tip of such insulators, so that in the same motors such plugs will not require cleaning after days and weeks of use. While this effect is present in the type of plug illustrated in my patent referred to above, I have found that by shielding the insulator and the larger part of the chamber 25 from the direct force of the explosion initiated at the spark gap 23, and probably also by reason of the suction effect in the chamber 25, there is no tendency for particles of carbon or of carbon-forming oil to be deposited within the chamber 25, to lodge upon any part of the insulator, particularly within the chamber 11.

In the form shown in Figures 1 and 2 a hot, concentrated spark is produced, yet the ball 22 serves to divide and direct outwardly the gases passing the spark gap and in this way keeps all parts of the plug free from oil and from carbon deposits, even when placed in engines which pump oil badly. In the form shown in Figure 3, while the ball is omitted this produces no material change in the general results. The gases appear either to be compressed within the dead air chamber 25 formed in the upper part of the skirt 32, between the upper parts of the skirt and the insulator 1, and to form thus a cushion which functions in lieu of the ball 22 to direct the gases outwardly through the ports 33, the flaring walls 34 of these ports assisting as before to direct these gases in a smooth curve, or the suction of the gases dividing and passing outward through these flared ports creates a suction within the chamber 25, drawing deposits or potential deposit-forming materials away from the projecting insulator.

In Figure 6 the negative electrode 35' has been shown as directed towards the ball 22, the tip 21 being omitted and the spark passing through the gap 23 between the ball 22 and the electrode 35'. This form retains the concentration of the spark without diminishing the self-cleaning effect of the gases moving past the ball and through the ports 33, the spark gap in fact being in the current of the gases.

In Figures 4 and 5 the enlargement of the lower end of the electrode 2 takes the form of a T-shaped head 22', this extending from the lower end of the electrode 2 towards the lower end of the apron 32. The spark takes place between one or both ends of the enlargement 22' and the skirt 32 itself. It will be noted that the ends of the head 22' are positioned relative to the apron 32 in

the same manner as the ends of the electrodes 35 and 2 in Figure 3, so that the spark at the gaps 23 jumps from the edge of the round end of head 22' to the inner edge of the lower end of the apron 32. While in this form the enlargement 22' serves to some extent to spread and direct the gases past the spark gaps 23 and through the ports 33, to a large extent the action in this form corresponds to that in the form of Figure 3.

One underlying idea in the present invention is the employment of a concentrated spark, between a negative and a positive electrode in the form of two wires, or one of which is replaced by a ball, or by the skirt itself, the other cooperating therewith to concentrate the spark. The principal inventive thought herein lies in the combination of members as just described, serving to produce a concentrated spark, with means for directing gases past the spark gap to maintain its elements clean, and to produce a suction or pressure to maintain the insulator clean, such means including the flared ports in the apron and either a positive deflector in the form of an enlarged or ball-shaped head on the electrode, or perhaps a passive deflector in the form of the cushion of dead gas in the upper part of the skirt. It departs from the invention disclosed in my previous patent, referred to above, in that the deflector ball does not cooperate directly with the apron to form an annular spark gap, but where employed, functions merely as a deflector, except as it may cooperate as in Figures 4 or 6, with a second electrode to form a concentrated spark.

What I claim as my invention is:

1. A spark plug comprising a shell terminating at its lower end in a depending substantially straight-side apron, open at its bottom, an insulator supported in said shell, an electrode extending through said insulator, said apron having a plurality of spaced ports, said electrode having an enlarged head formed thereon materially below the upper edges of said ports, said ports having outwardly flaring upper edges which, in conjunction with the enlarged head upon the electrode, direct a current of gases which pass upward through the annular space between the enlarged head and the apron, outwardly in a smooth curve, and a second electrode extending from the shell to the first electrode and cooperating therewith to form a spark gap positioned within the influence of such current of gas to be kept clean thereby.

2. A spark plug as in claim 1, the enlarged head being positioned slightly above the lower end of the first electrode, and said second electrode being directed toward the projecting tip of the first electrode, to form therewith the spark gap, and the enlarged head being formed to deflect the current of

gases outwardly and upwardly in all directions from said spark gap.

3. A spark plug comprising a shell terminating at its lower end in a depending substantially straight-side apron, open at its bottom, an insulator supported in said shell, and projecting within and spaced therefrom at its lower end to form a chamber above the lower ends of the insulator and apron, an electrode extending through said insulator, said apron having a plurality of spaced apertures above its lower end and substantially at the lower end of the insulator, communicating with the lower portion of said chamber, the end of said electrode being spaced from and cooperating with a complementary member to form a spark gap therebetween, said spark gap being positioned materially below the upper edges of said ports, and said upper edges being flared upwardly and outwardly, whereby gases passing the spark gap will be directed outwardly through said ports in a substantially smoothly curved path, whereby a current of gas is induced through the open end of the apron, and past the spark gap, to produce suction therein tending to maintain all elements within the influence of said gas current clean.
4. In a spark plug of the type comprising a substantially straight-sided shell freely open at its lower end and having upwardly and outwardly flared apertures thereabove and thereabout, an insulator projecting within the lower end of said shell and spaced therefrom, and an electrode held in said insulator and projecting therebelow and terminating substantially at the lower end of said shell, a deflector on the projecting portion of said electrode, the lower surface of said deflector being located below said flared apertures and being curved to

cooperate therewith to cause and direct outwardly in a smooth curve an upward current of gases entering the open end of said shell, and a second electrode cooperating with said first electrode to form a spark gap located within the influence of said current of gases to be maintained clean thereby, and so located, with respect to the deflector, that the interior of said shell is largely shielded by the deflector from the direct force of the explosion initiated at said spark gap.

5. In a spark plug of the type comprising a substantially straight-sided shell freely open at its lower end and having upwardly and outwardly flared apertures thereabove and thereabout, an insulator projecting within the lower end of said shell and spaced therefrom, and an electrode held in said insulator and projecting therebelow to position its tip substantially at the lower end of said shell, a deflector on the projecting portion of said electrode, the lower surface of said deflector being located below said flared apertures and being curved to cooperate therewith to cause and direct outwardly in a smooth curve an upward current of gases entering the open end of said shell, the tip of said electrode projecting below the lower surface of said deflector, and a second electrode cooperating with said tip to form a spark gap located within the influence of said current of gases, and so located, with respect to said deflector and said insulator, that the insulator is shielded by the deflector from the direct force of the explosion initiated at said spark gap, but is within the influence of suction created within the shell by said current of gases.

Signed at Victoria, British Columbia, Canada, this 24th day of March, 1925.

MAYNARD F. MACDONALD.
